UNITED STATES PATENT OFFICE.

HARRY W. BAGG, OF NEW BERLIN, NEW YORK.

DEVICE FOR PREVENTING COWS FROM LYING DOWN.

Application filed February 20, 1922. Serial No. 538,074.

To all whom it may concern:

Be it known that I, HARRY W. BAGG, a citizen of the United States, residing at New Berlin, in the county of Chenango and State of New York, have invented certain new and useful Improvements in Devices for Preventing Cows from Lying down, of which the following is a specification.

My invention relates to a device, for use in connection with a stanchion to prevent a cow from lying down after being washed or cleaned, preparatory to milking.

An important object of the invention is to provide a device of the above mentioned character adapted to be used in connection with the ordinary stanchion, and which will not be liable to inconvenience or injure the cow, while standing, and will permit of the ordinary movements of the stanchion, by the cow.

A further object of the invention is to provide a device of the above mentioned character, which is readily reversible so that it may extend in either direction.

25 A further object of the invention is to provide a device of the above mentioned character, so constructed that a plurality of them may be released by the operation of a single lever or the like.

30 A further object of the invention is to provide a device of the above mentioned character, which is simple in construction, cheap to manufacture, strong and durable.

Other objects and advantages of the invention will be apparent during the course 35 of the following description.

In the accompanying drawings forming a part of this specification, and in which like numerals are employed to designate like 40 parts throughout the same,

Fig. 1 is a side elevation of apparatus embodying my invention,

Fig. 2 is a vertical transverse section, taken on line 2—2 of Fig. 1, looking in the 45 direction of the arrows,

Fig. 3 is a horizontal section taken on line 3—3 of Fig. 1,

Fig. 4 is an enlarged side elevation of the device, showing it in the raised position,

50 Fig. 5 is a plan view of the same,

Fig. 6 is a side elevation of the vertically adjustable supporting sleeve or element, associated elements being shown in section,

Fig. 7 is a horizontal section taken on line 55 7—7 of Fig. 6, and,

Fig. 8 is a detail section taken on line 8—8 of Fig. 6.

In the drawings, wherein for the purpose of illustration is shown a preferred embodiment of my invention, the numeral 10 designates a supporting frame, as a whole, including a horizontal bar or tube 11, and vertical posts or tubes 12 connected therewith and supporting the same. Curved laterally extending bars 13 are connected with the 60 bars 12 and extend downwardly for connection with the floor 14, preferably formed of concrete. The bars 12 divide the structure into a number of stalls 15, as is well known.

Arranged at the forward end of the stalls 70 are stanchions 16, which may be of any well known or preferred type. These stanchions are pivotally supported at their upper ends by links 17, secured to sleeves 18, which in turn are mounted upon the upper tube 11. 75 Chains 19 or other flexible elements serve to connect the lower ends of the stanchions with the floor 14.

The device to prevent the cow from lying down comprises an arm or bar 20, which is 80 preferably tubular, and has its free end bent into a curved point or neck 21, so that the cow may not be injured. The inner end of the arm extends into a tubular socket 22, rigidly secured upon a flat head or disk 23, and 85 preferably formed integral therewith. The head or disk 23 is provided with a central opening 24 (Fig. 7) to pivotally receive a cylindrical extension or trunnion 25, formed upon a head or disk 26. The extension or trunnion 25 has a reduced screw threaded extension 27, forming a shoulder 28. The extension 27 receives a cap or head 29; held thereon by a nut 30. It is thus seen that the shoulder 28 will engage with the head or cap 90 29, and the head or disk 23 will be free to swing upon its pivot 25.

The head or disk 26, Fig. 6, is provided with a pair of rearwardly extending apertured knuckles or ears 31 and 32, preferably 100 formed integral therewith. These ears or knuckles are arranged within ears or knuckles 33, and the two sets of knuckles are pivotally connected by means of a vertical bolt or pivot pin 34. The ears 33 are 105 preferably formed integral with one element 35 of a tubular clamp or sleeve, the coacting element 36, being adjustably secured thereto by bolts 37 or the like. It is obvious that this sleeve or clamp may be vertically ad- 110

justed upon the post 12, and clamped thereto at the desired position.

Surrounding the bolt or pivot element 34, between the ears 31 and 32, is a coil spring 38, one end of which contacts with the clamp or sleeve element 35, and the other end with the head or disk 26, Figs. 6 and 7. The function of this spring is to swing the head or disk 26 in one direction upon its pivot, for normally retaining the arm 20 substantially parallel with the stanchion 16. The lower ear or knuckle 32 is provided with a pair of lateral extensions 39, having screw threaded openings 40. A stop bolt 41 may be adjustably mounted in either of these openings, and carries a lock nut 42. The stop bolt 41 is adapted to engage with either stop lug 43, cast integral with the sleeve element 35. When the arm 20 extends to the left, the spring 38 has its ends engaging the right-hand portions of the sleeve element 35 and head 26, and the stop bolt 41 will then engage the left-hand stop leg 43. If the arm 20 is reversed so that it extends to the right, the spring 38 and stop bolt 41 are reversed, so that the spring will then function to swing the arm 20 and its head 26 in an opposite direction, retaining it parallel with the stanchion. The stop bolt 41 will then engage the stop leg 43, to the right.

In order that the arms 20 may be locked in the horizontal position, their heads or disks 23 are provided with a pair of diametrically oppositely arranged openings or notches 44, adapted to receive reciprocating bolts 45, slideable within guides or housings 46, preferably formed integral with the ear 31 and head or disk 26, as shown in Fig. 6. The bolts 45 are provided with slots or recesses 47, receiving screws 48, or like elements. The bolts are provided with shanks 49, and are urged downwardly by springs 50, surrounding the shanks within the housings 46. It is thus seen that when the arm 20 is swung to the horizontal position, that the bolt will automatically enter the opening or notch 44 and lock the arm in this position. A pair of notches 44 are provided in each disk, so that the notches will function properly when the arms 20 are reversed.

Means are provided to simultaneously operate the several bolts 45, including cables 51, extending upwardly for connection with cranks 52, which are rigidly mounted upon a rock shaft 53. This rock shaft is journaled within stationary bearings 54, and is turned by a lever 55, as shown.

In operation, after the cows have been washed or cleaned, while standing in the stanchions, the arms 20 are shifted upwardly to the horizontal position. As soon as they assume these positions, the bolts 45 automatically enter the notches 44, and the

arms are thus locked against vertical swinging movement. The arms 20 will prevent the cows from lying down, but does not interfere with the ordinary movement of the stanchions. A cow may shift the stanchion laterally, or turn the same upon its pivot, as shown in Fig. 3, and this movement of the stanchion will swing the arm 20 forwardly, the same turning upon the pivot 34. By these means any sudden movement or lunge of the cow will not break the stanchion or arm 20 or injure the cow. When it is desired to lower the arms, the operator may swing the lever 55 upwardly and all of the bolts 45 will be retracted from the notches 44, and the arms 20 will gravitate to the lowered or vertical position.

It is to be understood that the form of my invention herewith shown and described is to be taken as a preferred example of the same, and that various changes in the shape, size and arrangement of parts may be resorted to without departing from the spirit of my invention or the scope of the subjoined claims.

Having thus described my invention, I claim:

1. The combination with a loosely supported stanchion for receiving the neck of a cow or the like and capable of packing of restricted movements, of a relatively stationary support spaced from the stanchion, and an arm mounted upon the support and adapted to extend across the stanchion and normally serving to prevent the cow from reclining, said arm being shiftable upon its support to occupy a position substantially upon one side of the stanchion.

2. The combination with a stanchion for receiving the neck of a cow or the like, of a support separate from the stanchion and arranged near the same, an arm pivotally connected with the support to swing substantially vertically and extending across the stanchion to normally prevent the cow from reclining, said arm being shiftable upon its pivot to assume an approximately vertical position, and means to lock the arm in the operative position across the stanchion.

3. A substantially stiff arm adapted to extend approximately horizontally across a stanchion to prevent a cow or the like from reclining, a separate relatively stationary support arranged near the stanchion and having the arm mounted thereon, and means adjacent to the support to hold the arm in the operative position.

4. A substantially stiff arm adapted to extend approximately horizontally across a stanchion to prevent a cow or the like from reclining, a relatively stationary support spaced from the stanchion, means for pivotally connecting one end of the arm with the relatively stationary support, and means

engaging the arm near its pivotal connection to hold the same in the approximately horizontal position.

5. A substantially stiff arm adapted to extend approximately horizontally across a stanchion to prevent a cow or the like from reclining, means for pivotally supporting the arm so that it will swing substantially vertically and will gravitate to an approximately vertical position when released, means to lock the arm in the raised position, and means to operate the locking means to release the arm.

6. An arm adapted to extend generally horizontally upon one side of a stanchion for preventing a cow or the like from reclining, a support arranged near the stanchion and separate therefrom, and means for connecting the arm with the support so that the arm may swing substantially horizontally.

7. An arm adapted to extend generally horizontally across a stanchion for preventing a cow or the like from reclining, means for supporting the arm so that it may swing substantially horizontally, and resilient means to oppose such swinging movement.

8. An arm adapted to extend generally horizontally upon one side of a stanchion for preventing a cow or the like from reclining, a horizontally swinging support, yielding means to oppose the swinging movement of the support, means to pivotally connect the arm with the support so that the arm is adapted to swing vertically with relation thereto, and means to lock the arm to the support against vertical swinging movement.

9. An arm adapted to be arranged upon one side of a stanchion, a head carrying the arm and having a central opening and a pair of oppositely arranged notches, a supporting element extending within the central opening of the head and upon which the head is removably mounted and adapted to be arranged thereon in reverse positions, and a bolt carried by the supporting element and adapted to enter one of said notches when the arm is swung to the operative position.

50 10. A supporting element arranged upon one side of a stanchion, a head pivoted to

the supporting element to turn in a horizontal plane, said head carrying laterally extending elements, a stop element adapted for connection with either lateral extending element and adapted to contact with a portion of the supporting element, a reversible spring serving to swing the head in one direction, and a reversible arm carried by the head and adapted to project upon one side of the stanchion.

11. A relatively stationary supporting structure, a plurality of stanchions loosely suspended from the supporting structure and capable of partaking of restricted movements, arms adapted to extend generally horizontally across the stanchions, means for pivotally connecting said arms with the supporting structure so that said arms may gravitate to approximately vertical positions when released, locking devices for holding the arms in the raised positions, and common means to operate said locking devices.

12. A relatively stationary supporting structure, a plurality of stanchions loosely suspended therefrom, a plurality of supporting elements pivotally mounted upon the supporting structure near the stanchions to swing substantially horizontally, arms pivotally mounted upon the supporting elements to swing substantially vertically and adapted to extend across the stanchions, springs to swing the arms substantially horizontally toward the stanchions, devices to lock the arms against vertical swinging movement, and means to operate the devices.

13. A relatively stationary supporting structure, a plurality of stanchions connected therewith, a plurality of arms adapted to extend across the stanchions and having heads provided with notches, means for pivotally connecting the heads with the supporting structure so that the arms may swing substantially vertically, bolts mounted upon the supporting structure adjacent to said heads, springs to move the bolts toward the heads to enter said notches, and common means to move said bolts away from said heads.

In testimony whereof I affix my signature. 100

HARRY W. BAGG.
